Primary Examiner — Mark Goodwin(74) *Attorney, Agent, or Firm* — Brian J. Teague(57) **CLAIM**

I claim the ornamental design for a device for supporting an object, as shown and described.

DESCRIPTION

FIG. 1 is a perspective view of a device for supporting an object showing my new design;

FIG. 2 is a front elevational view thereof;

FIG. 3 is a rear elevational view thereof;

FIG. 4 is a top view thereof; and,

FIG. 5 is a bottom view thereof.
